UNITED STATES PATENT OFFICE.

WILLIAM H. RANKIN, OF LAWRENCE, MASSACHUSETTS.

CARDING-MACHINE.

SPECIFICATION forming part of Letters Patent No. 365,405, dated June 28, 1887.

Application filed September 21, 1886. Serial No. 211,149. (No model.)

To all whom it may concern:

Be it known that I, WILLIAM H. RANKIN, of Lawrence, county of Essex, and State of Massachusetts, have invented an Improvement in Carding-Machines, of which the following description, in connection with the accompanying drawings, is a specification, like letters on the drawings representing like parts.

This invention has for its object to improve 10 that class of carding-machines wherein the top-flats are oscillated or turned partially upward from the card-cylinder to be stripped. In my Patent No. 336,587 the top-flats or segmental workers were oscillated by a rack-and-pinion 15 movement carried by the traveling frame. Herein I have devised means whereby each top-flat is grasped at the end by a jaw connected with an oscillating or rock shaft, the movement of which is controlled by a cam 20 carried by the traveling frame, the said cam being rotated at such speed with relation to the movement of the traveling frame as to enable the jaw to take hold of every alternate top-flat. The jaw referred to is loosely connected 25 with the rock-shaft, and is made to slide longitudinally thereon under the control of a pattern-cam so shaped as to cause the jaw to grasp alternate top-flats or to skip one or more top-flats, as desired.

30 My invention consists, essentially, in a card-cylinder, a series of pivoted top-flats having shoes, the frame A, the rock-shaft f^4 , and a jaw thereon, combined with means to rock the said shaft while its jaw is in engagement 35 with a shoe of a top-flat, to overturn the said top-flat, substantially as will be described.

Figure 1 is a side elevation of a sufficient portion of a carding-machine to illustrate my invention, the arch being broken out to show 40 a part of the cylinder, the said figure showing but a small number of the top-flats, as all are alike. Fig. 2 is a right-hand end elevation of Fig. 1; Fig. 3, an outer side view, on a larger scale, of a portion of the traveling frame and 45 parts carried by it, the top-flat (shown by dotted lines) being in position to be stripped. Fig. 4 is a right-hand side view of Fig. 3. Fig. 5 is a section of Fig. 4 on the dotted line $x-x$, looking to the left. Fig. 6 is a detail of the 50 one-toothed gear, to be described. Fig. 7 is a detail showing one end of one of the top flats; and Fig. 8 is a detail of the shoe n , to be described.

The card-clothed cylinder A³, its shaft A²,

the traveling frame A, pulley r on the main 55 shaft A², the belt e , pulley d , pinion a at its rear side, toothed gear b , driven by it, and the pinion c at its rear side, and the cam-gear B³, are all the same as in the well-known "Wellman" stripper, or as in United States 60 Patent No. 291,471. Herein, however, the cam-groove B³ has at its face a cam of different shape to vibrate the top-flat stripping-card, and at its rear side the said gear has a peculiar cam, to be described, which aids in 65 effecting the partial overturning or oscillation of the top-flats.

In practice the traveling frame will be moved through the medium of a pinion set in motion intermittently by the toothed periphery of the said cam-gear B³, the said pinion engaging a curved rack, secured to the side frame of the carding-machine, substantially as shown in the said patent, and being not of my invention, but well known, need not be 70 herein further described. The periphery of the cam-gear B³ for about ninety degrees is provided with teeth extending entirely across the said periphery; but for the remaining two hundred and seventy degrees the said cam- 80 gear has a series of short teeth lying at the side of a smooth or untoothed surface, against which co-operates the holding segment 2, it and a pinion, e^2 , being fast on a short shaft, 4, extended through the carrying-frame and provided with a gear, 5, having a tooth, 15, (see Figs. 5 and 6,) which tooth at each rotation of the said shaft engages the crown-teeth 6 of a gear, 7, and moves it one step or tooth, the said gear 7 at its periphery having a series of 85 scallop teeth, 8, which are entered by the toothless portion of the gear 5, the said toothless portion entering one of the said scalloped spaces as the tooth 15 passes from engagement with the crown-teeth 6, the gear 7 being 90 held at rest as long as the untoothed semicircular portion thereof remains in the said scallop.

In Fig. 5 it will be noticed that the tooth 15 stands back from the front of the gear 5, and 100 that the front of the said gear is circular for substantially three hundred degrees, as shown in Fig. 6, the remaining portion of the gear being cut away in line with the tooth 15, thus leaving a space for the large or untoothed part 105 of the gear to run in and out of mesh with the scalloped part of the gear 7. The gear 7 is attached to a pattern-cam, 10, mounted loosely

on a stud, 12. The pattern-cam has a groove, 13, (see Figs. 2 and 4,) which receives in it one end of a lever, 14, pivoted at 16 on a stand secured to the traveling frame A, the upper end of the said lever being forked to enter an annular groove in the neck of the jaw f, having an open space, f', and a tubular shank, the space in the said jaw being of suitable size and shape to receive in it a shoe, 29, (see Figs. 2 and 7,) with which each top-flat is provided at one end, the said shoe being at the extremity of the top-flat and outside of the bearings 44, common to my patent No. 336,587, the said bearings being erected upon the arch of the card-frame, the said bearings in practice being preferably made adjustable in any usual manner. Each top-flat has its journal 30 near one edge at each end thereof, the journals at one end of each top-flat having a shoe, 29, the journals being near one edge of the top-flat, as shown, to thus permit the top-flats to be readily overturned, substantially as in my said patent. The sleeve of the jaw f is splined on an oscillating shaft, f', and is moved longitudinally thereon by the lever 14, according to the requirements of the pattern-cam, the jaw being moved to the right in the arc occupied by the shoes, and being there retained as long as alternate top-flats are to be oscillated or turned over to be stripped. By making the cam so that about two hundred and seventy degrees of the groove compels the lever to keep the jaw out in the line of and so as to pass over the shoes, the remaining ninety degrees acting upon the lever 14 to draw the jaws out of the range of the shoes, it is possible with a carding-machine having twenty flats (the traveling frame being supposed to make two complete trips over and back) to strip every alternate flat of the first 40 ten flats, omit the next ten both when going over and back, then during the last part of the first trip back strip the alternate flats lying between those of the first ten flats which were stripped first, and during the second trip both backward and forward all the flats are stripped alternately. Of course the order of stripping may be changed by changing the shape of the groove in the pattern-cam. The shaft f', to which the sleeve having the jaw f, 50 is connected, is extended through the traveling frame A, and outside the frame has connected to it a foot, n, concaved, as at 17, (see Fig. 8,) and provided with a pin or stud, 18. The rear side of the cam-gear B³ differs from 55 the cam-gears common to the one shown by like letter in United States Patent No. 291,471, and also common to the Wellman stripper, as referred to, in that the inner side of the said cam-gear, as devised by me, is shaped as shown 60 in Fig. 5. This cam-gear has a cam-groove, 20, which receives in it the pin or stud 18, and, acting thereon, causes the shaft to be rotated for nearly half a rotation, the concaved part 65 of the said foot co-operating with and fitting snugly against the convexed or segmental shelf 22, when the pin or stud 18 is in that part of the said cam-groove 20 nearest the

periphery of the said toothed cam B³, the said foot and shelf acting to insure the firm holding of the top-flat in position with its card-teeth uppermost to be stripped by the stripping device, which, operating at that time, strips the top-flat. The top-flat having been stripped, the concaved portion of the foot is released from the shelf 22, and the pin or stud 18 in the farther rotation of the cam B³ enters the portion 23 of the cam-groove 20, and the shaft f' is oscillated in the opposite direction to return the top-flat into working position, the jaw, when it comes in position to place its open portion f' in line with the shoes g, being carried by the movement of the traveling frame into position to embrace a shoe of a neighboring top-flat, which is then raised, as before stated.

The card S employed, by which to strip the overturned top-flats, and the mechanism to operate it are all as fully shown and described in my patent referred to, No. 336,587, so need not be herein further described. The main frame F is of the same shape as the main frame in my patent referred to. The cam 20 might be composed of a single flange, instead of two, as shown in Fig. 5, and in such event two pins or studs 18 would be used—one against each side of the flange.

I claim—

1. The carding-cylinder, a series of pivoted top-flats having shoes, the frame A, the rock-shaft f', and a jaw thereon, combined with means to rock the said shaft while its jaw is in engagement with a shoe of a top-flat to overturn the said top-flat, substantially as described.

2. The carding cylinder, a series of pivoted top-flats having shoes, the frame A, the rock-shaft f', and a jaw thereon, combined with means to rock the said shaft while its jaw is in engagement with a shoe of a top-flat, and with a pattern-cam, a lever moved by it to move the said jaw toward and from the top-flats in the direction of their length, and with means to rotate the said pattern-cam, substantially as described.

3. The frame A, the cam-gear B³ thereon, provided at its rear side with a cam and with a segmental shelf, and a rock-shaft having a foot provided with a pin or stud to co-operate with the said cam, and with a concaved surface to co-operate with the said shelf, and a jaw carried by the said rock-shaft, combined with a main cylinder and with a series of pivoted top-flats provided with shoes to be engaged by the said jaws, the said foot and shelf holding or locking the top-flat in position while it is being stripped, substantially as described.

In testimony whereof I have signed my name to this specification in the presence of two subscribing witnesses.

WILLIAM H. RANKIN.
